UNITED STATES PATENT OFFICE.

JOSEPH STRAND, OF LOS ANGELES, CALIFORNIA, ASSIGNOR TO KLINCH LATH CORPORATION, A CORPORATION OF CALIFORNIA.

PLASTER BOARD.

Application filed June 25, 1924. Serial No. 722,266.

My present invention is referred to as a staple-key plaster board for the reason that it involves the use of metallic fastening devices, such as ordinary staples, preferably 5 extending across slots, of any usual or preferred character, in a plaster board adapted to be provided with an additional coating, such as an inner finishing coat or an outer protective coat; and it is an object of 10 this invention to provide simple and effective means serving not only to offset any weakening effect arising from the provision of "key" slots or depressions in plaster board, but serving also and more especially 15 to aid in the retention of the key of a coating material within such slots or depressions, regardless of whether such slots are formed with inclined or with perpendicular walls, and regardless of whether or not they 20 are formed by a cutting operation executed upon a preformed slab.

This invention relates particularly to a plaster board structure in which staples, or the like, are employed, in conjunction with 25 slots preformed in a plaster board, to aid in the retention of a coating thereon; and said plaster board may comprise a slab of plastic material, of any usual or preferred character, provided on one or both of its 30 substantially flat faces with a sheet of fibrous material such as paper, outside of which my reinforcing and key-retaining devices such as staples extending across the mentioned slots, may be clinched.

35 Other objects of my invention will appear from the following description of an advantageous embodiment thereof, taken in connection with the appended claims and the accompanying drawings, in which

40 Fig. 1 is a perspective view of a corner of a slab of plaster board embodying the features of my present invention.

Fig. 2 is a vertical or transverse section in a plane such as is indicated by the line 45 2-2 of Fig. 1, a coating being indicated as applied and "keyed" to said slab.

Referring to the details of that specific embodiment of my invention chosen for purposes of illustration, 11 may be a body of plastic material to the opposite faces of which layers 12, 12' of paper or a similar fibrous material are preferably applied, slots 13, 13' being shown as arranged in separate linear series with their longitudinal axes extending substantially at right angles, and

each slot being provided with a staple or staples 14, shown as extending thereacross. The respective slots may be of any desired depth and configuration, although it will be obvious that, if wall paper is to be applied 60 directly to one surface of my wall board, the mentioned slots should not extend entirely therethrough, and obvious also that, in the case referred to, the points of the staples 14, or their equivalent, should not be permitted to project beyond the inner or smooth 65 surface of said plaster board.

I consider it advantageous, in order to utilize the staples 14, or their equivalent for both a reinforcing and a keying effect in 70 the retention of a coating 15, or its equivalent, to provide the same with comparatively sharp points 16, and to rebend or clinch these points in such manner as to preserve the smoothness of the lower or inner 75 surface, shown as provided with the mentioned layer of fibrous material 12', through which said points extend. By this construction, it will be obvious that, whether or not the slots 13, 13' are under-cut, the "key" projections 17, or their equivalent, are so retained as to prevent the separation of the coating 15, without an actual breakage of 80 said key projections.

Staples extending slightly above the plaster board may optionally be used without slots; and although I have herein described one complete embodiment of my invention, it will be understood that various features 85 thereof might be independently employed, 90 and also that various modifications might be made by those skilled in the art, without the slightest departure from the spirit and scope of my invention, as the same is indicated above and in the following claims. 95

I claim as my invention:

1. A plaster board comprising: a slab of plastic material having key slots formed in the face thereof, said slots having side walls substantially perpendicular to said face; and 100 individual metallic fastening devices extending across said slots.

2. A plaster board comprising: a slab of plastic material having key slots formed in the face thereof, said slots having side walls substantially perpendicular to said face and said slots being arranged in series with their longitudinal axes extending in a plurality of directions; and individual metallic fastening devices extending across said slots.

3. A plaster board comprising: a slab of plastic material having key slots formed in the face thereof, said slots having side walls substantially perpendicular to said face and said slots being arranged in series with their longitudinal axes extending in a plurality of directions; and individual metallic fastening devices extending transversely across said slots.
- 10 4. A plaster board comprising: a slab of plastic material having key slots formed in the face thereof, said slots conforming in outline to a segment of a disc; and individual plaster retaining means consisting of staples driven partially into said slab and
5. A plaster board comprising: a body of plastic material having recesses formed therein, said recesses conforming in outline to a segment of a disc; and individual metallic plaster retaining devices extending across said recesses, said devices consisting of staples driven into said body and the ends clinched therein.

In testimony whereof, I have hereunto set my hand at Los Angeles, California, this 12th day of June, 1924.

JOSEPH STRAND.
